[57] CLAIM

The ornamental design for a stunt kite, as shown and described.

DESCRIPTION

FIG. 1 is a top perspective view of a stunt kite showing my new design.

FIG. 2 is a bottom perspective view thereof.

FIG. 3 is a rear elevational view thereof.

FIG. 4 is a top plan view thereof.

FIG. 5 is a bottom plan view thereof.

FIG. 6 is a front elevational view thereof.

FIG. 7 is a right side elevational view thereof, the side opposite being a mirror image.

FIG. 8 is a modified embodiment of the design shown in FIGS. 1 through 7.

FIG. 9 is a second modified embodiment of the design shown in FIGS. 1 through 7.

FIG. 3

FIG. 4

FIG. 5

FIG. 6

FIG. 7

FIG. 8

FIG. 9
